UNITED STATES PATENT OFFICE.

GEORGE R. LAWRENCE, OF CLEVELAND, OHIO, ASSIGNEE TO THE LOEW MANUFACTURING COMPANY, OF CLEVELAND, OHIO, A CORPORATION OF OHIO.

MACHINE FOR CLEANING BOTTLES AND LIKE ARTICLES.

13,250.

Specification of Reissued Letters Patent. Reissued May 30, 1911.

Original No. 932,145, dated August 24, 1909, Serial No. 350,279. Application for reissue filed October 15, 1910. Serial No. 587,347.

To all whom it may concern:

Be it known that I, GEORGE R. LAWRENCE, a citizen of the United States, residing at Cleveland, in the county of Cuyahoga and 5 State of Ohio, have invented a certain new and useful Improvement in Machines for Cleaning Bottles or Like Articles, of which the following is a full, clear, and exact description, reference being had to the accompanying drawings.

This invention relates to machines for cleaning bottles or like articles, and it has particular reference to a device for cleaning the interior of bottles, that is shown in the 15 patent to Loew, No. 700,518.

While the device is particularly applicable to bottle cleaners of the type shown in said patent, it is not necessarily limited to use therewith, but may be employed in connection with interior cleaners for bottles of different types from that shown.

In the drawings forming a part of this application, Figure 1 is a side elevation of a machine for cleaning the interior of bottles, 25 the said machine having my improved exterior cleaning device applied thereto. Fig. 2 is a side elevation of my invention looking at the same from the side opposite that of Fig. 1, said view also showing a portion of 30 the interior cleaning mechanism and the manner in which my invention is attached thereto. Fig. 3 is a longitudinal sectional view through my cleaning device, taken substantially on the line 3—3 of Fig. 4, and Fig. 35 4 is a plan view of my cleaning device, said view being taken substantially on the line 4—4 of Fig. 3.

As has been stated, and as is shown in the patent above referred to, devices for cleaning the interior of bottles with rapidity and in large quantities are well known and are commercially successful. In such devices, however, the exteriors of the bottles have not been thoroughly cleansed, which cleaning requires a subsequent operation. With 45 my exterior cleaning device applied to one of said machines, the bottles will be cleaned both on their interior and exterior surfaces and will thereby be placed in condition for 50 refilling.

Taking up a more detailed description of the invention by reference to the accompanying drawings, 1 represents the vat or tank

of what I shall herein term the interior cleaner, said tank being divided by a partition 2, into a plurality of separate compartments for the cleansing liquids. Within each of said compartments, I mount sprocket wheels 3 on each side of the vat, upon which wheels there is mounted an endless carrier 4, 55 for the bottles, said carrier being provided with baskets or receptacles 5 into which the said bottles are placed. Above the partition or partitions 2, I mount sprocket wheels 6, 60 at each side of the machine, over which the carrier 4 is conducted, said wheels 6, lifting the carrier and the bottles therein above the partition and into position to be submerged in the next adjacent compartment of the vat. Also at the forward end of the vat or tank, 65 and above the latter, I journal sprocket wheels 7 and 8, there being one set of these wheels at each side of the machine. The endless carrier 4 also passes around these 70 wheels. Inasmuch as this part of the structure is the same in principle as that shown and described in the patent above referred to, it is not deemed necessary to enter into a fuller description thereof.

Referring now more particularly to Fig. 80 2 of the drawings, 9 represents a pulley which is keyed, or otherwise secured, to a shaft 10, said shaft being journaled in a bracket 11 that is secured to the side of the vat 1. 12 is a loose pulley also on said shaft, 85 it being understood that when the driving belt is upon said loose pulley, no power will be transmitted to the mechanism of the machine. Also secured to the shaft 10 is a pinion 13, said pinion meshing with a gear 14, 90 on a shaft that is parallel with the shaft 10 and that is also journaled in the bracket 11. The latter shaft is provided between its bearings with a worm 15, said worm gearing with a worm wheel 16 that is keyed, or 95 otherwise secured, upon the shaft 17, said shaft having secured thereto one pair of the sprocket wheels 3, within the vat 1. By means of the shaft 17 and the train of gearing thus described, the endless belt 4 is 100 caused to travel in the direction of the arrow, shown in Fig. 1. Also secured to the shaft 10 is a pinion 18, said pinion meshing with a gear 19 on a shaft 20 that is journaled in bearings upon the side of the vat 1. The 105 gear 19 has secured to one side thereof a pin-

ion 24, which meshes with a gear 22 on a shaft 23, said shaft extending forwardly in a direction parallel with the shaft 10.

Projecting rearwardly from the tank or vat 1 at each side thereof are frame pieces 24, preferably channel irons, said pieces being supported at their forward ends upon legs 25. The shaft 23 is journaled in brackets 26 on these frame pieces, and extends to a point substantially midway of the length of frame pieces 24. Mounted in suitable bearings, which are carried by the frame pieces 24, are transverse shafts 27 and 28, the bearings for the latter shaft being adjustable by means of screws 29 so that the distance between the shafts may be varied. Secured to the shafts 27 and 28 near their ends are sprocket wheels 30 and 31, upon which there is mounted, at each side of the machine, sprocket chains 32. Extending across from one of these chains to the other, and on the outside thereof, are a series of strips or cleats 33, said cleats being so mounted on the chains and so placed with reference to one another that they form a practically continuous belt. By means of the adjustment for the bearings for the shaft 28, above described, the said belt may be tightened or loosened as desired. Hereinafter, in order to distinguish from the carrier 4 of the interior cleaner, I shall refer to the said belt as the belt carrier.

The sprocket wheels 30 are mounted substantially beneath the large sprocket wheels 8 for the interior carrier, so that the said interior carrier projects over the front end of the belt carrier for the exterior cleaner. Mounted upon the interior cleaner, below the sprocket wheels 8, is a curved plate 34, said plate extending transversely across the machine so as to support the bottom of the bottles 35 while they are within the baskets or receptacles 5. This plate 34 terminates above the sprocket wheels 30, and an inclined chute 36 extends downwardly and forwardly from the forward edge of said plate. As the sprocket wheels 8 rotate in the direction of the arrow shown in Fig. 3, the bottles will slide out of their baskets 5 as soon as they have passed the said plate, and will be conducted by the chute 36 to the belt carrier on the exterior cleaner.

For driving the belt carrier, a bevel pinion 37 is secured to the shaft 23, said pinion meshing with a bevel gear 38 that is keyed, or otherwise secured, to the shaft 27.

From the description thus given, it will be understood that both of the said endless carriers are moved with comparatively slow speed, the carrier for the exterior cleaner moving in the direction of the arrow shown in Figs. 2 and 3. Spaced suitable distances apart on said carrier, and connected to the transverse cleats 33 thereof, are outwardly projecting brushes 39, against which the bot-

tom of the bottles are adapted to be pressed, as they are being cleaned, or scrubbed, by the mechanism now to be described.

Projecting upwardly from the frame pieces 24 are plates or housings 40, within which are journaled transverse shafts 41 and 42, said shafts being provided, toward their central portions, with pairs of sprocket wheels 43 and 44. Upon each pair of said sprocket wheels there is mounted a sprocket chain 45 to which is secured transverse cleats 46, said cleats being similar to the cleats 33 heretofore described. Projecting from the outer faces of these cleats are bristles 47, said cleats being so closely positioned that the bristles will be practically continuous. I shall, therefore, call this part of the mechanism the endless brush. The shaft 41 is driven from the shaft 10, as shown in Fig. 2, by means of a pulley 48 that is secured to the latter shaft, said pulley having an endless belt 49 passing thereabout, and thence over a pulley 50 on the said shaft 41. As the pulleys 48 and 50 are in planes at right angles to each other, the belt 49 is properly guided by the guide pulleys 51 and 52 in a manner well understood. Inasmuch as the shaft 10 is driven at a high rate of speed, as compared with the shaft 23, which drives the belt carrier, and the pulley 50 is smaller in diameter than the pulley 48, the endless brush travels at a much higher velocity than the bottles which lie upon the cleats 33 of the belt carrier. When the bottles are deposited upon said carrier, they move forwardly therewith until they are engaged by the rotary brush 47, which will sweep the bottles forward into contact with the brushes 39. The said endless brush cleans the curved surfaces of the bottles, while the bottoms thereof are cleaned by the brushes 39. To facilitate the cleaning of the bottles, the endless brush is given a transverse movement with respect to the belt carrier, which movement rolls the bottles transversely of the carrier, thereby causing the bottoms of the bottles to be thoroughly cleaned by the brushes 39. This transverse movement is effected by a bevel pinion 53, on the forward end of the shaft 23, which pinion meshes with a bevel pinion 54 on a short vertical shaft that is mounted in bearings 55 on the side of the housing 40. The upper end of said vertical shaft is provided with a crank 57, the pin of which projects into an elongated slot 58 in a yoke plate 59 that is mounted upon one of the ends of the shafts 41 and 42. The rear end of said plate 59 is bifurcated and is provided with eye-pieces for the shaft 41, the pulley 50 being secured to the shaft between the bifurcations of the plate. The forward end of the plate is also bifurcated, while a collar 60 is secured to the shaft 42 between the said bifurcations. Instead of having eye-pieces at the forward

end of the plate 59, said plate is simply forked in order to provide for the adjustment of the shaft 42, which is effected by means of screws 61, shown in Fig. 4, said adjustment tightening or loosening the brush, as may be desired. As the crank 57 rotates, the plate 59 will be moved laterally, which movement will result in shifting the shafts 41 and 42 transversely of the carrier, the 10 said shafts being elongated at their ends opposite said plate to provide for such lateral movement.

Owing to the comparatively slow speed of the exterior carrier and the relative size 15 of gears 53 and 54, the brush will be given at least one complete reciprocation during the passage of the bottles therebeneath. This causes the bottles to be rolled in reverse directions during their excursion beneath 20 the brush, thereby insuring a thorough cleaning of the sides and bottoms of the bottles. As the brushing device is in effect mounted upon rollers during its reciprocation (the bottles acting like rollers during 25 their lateral movement), it follows that there is a relative lateral movement between the bottles and the brushing devices as well as between the bottles and the carrier, since the brushing device will travel faster in its 30 lateral movements than do the bottles.

In Fig. 4, I have shown a portion of the chute 36, for conveying the bottles to the endless carrier. This chute is longer than the width of the rotary brush; and, for the 35 purpose of taking up all space between the bottles on the belt carrier, I secure to the shafts 41 and 42 downwardly projecting arms 62, to the lower ends of which are secured plates 63, said plates extending parallel with each other opposite the endless brush, but diverging at the front of the same, and passing upon opposite sides of the chute 36. As the bottles drop upon the belt carrier and are moved toward the brush, 45 the diverging parts of these plates will roll the bottles toward the center of the carrier and thereby concentrate them under the brush. The front ends of the plates 63 are supported by a stationary transverse bar 63a.

50 In order that my improved cleaning device may be adapted for all diameters of bottles, I have provided means for adjusting the belt carrier with reference to the endless brush, said means consisting of parallel plates 64 which are mounted upon the ends of links 65, there being one of these plates and a set of said links at each side of the carrier. The plates 64 are beveled at their ends, and, at their centers, they form a 55 support for the belt carrier. When the plates are moved rearwardly, or to the right in Fig. 3, they tend to move away from the said carrier and thereby permit the same to recede from the brush. This movement 60 of the plates 64 is effected by means of con-

necting rods 66 which extend from said plates to cranks 67, which are secured to a transverse shaft 68. To one end of the shaft 68, I secure a hand wheel 69, by means of which said shaft may be turned. As the shaft is thus turned, the cranks 67 move the plates 64 backwardly or forwardly, as desired, and, in so doing, said plates are lowered or lifted and the endless carrier is thus adjusted with respect to the endless brush. 75 For the purpose of holding the plates 64 in any position to which they may thus be moved, I secure to the shaft 68 a ratchet or gear wheel 70, with which engages a suitable detent pawl 71.

80 While I have shown and described means for shifting the brush laterally and for moving the belt carrier toward the brush, it will be readily seen that the same results in the operation of the device can be effected by shifting the carrier laterally and by raising and lowering the brush. The following claims that call for a relative movement of these parts are intended, therefore, to cover either of these arrangements.

90 Having thus described my invention, I claim:

1. In a machine for cleaning bottles or like articles, a carrier for the bottles, means for driving said carrier at a relatively slow speed, means coöperating with said carrier for cleaning the exterior of the bottles, and means for producing a relative lateral movement between the carrier and the cleaning means whereby the bottles are turned as they are being cleaned. 95

2. In a machine for cleaning bottles or like articles, a carrier for the bottles, means for driving said carrier at a relatively slow speed, a brush so arranged with respect to the carrier that the bottles will be brushed thereby as they are in transit on the carrier, and means for producing a relative transverse movement between the carrier and the brush, whereby the bottles will be turned on the carrier as they are being cleaned. 105

3. In a machine for cleaning bottles or like articles, a carrier for the bottles, means for driving said carrier at a relatively slow speed, a traveling brush so arranged with respect to the carrier that the bottles will be brushed thereby as they are in transit on the carrier, means for driving said brush at a relatively high speed, and means for moving said brush transversely of the carrier, whereby the bottles will be turned on the carrier as they are being cleaned. 115

4. In a machine for cleaning bottles or like articles, a carrier for the bottles, means for driving said carrier at a relatively slow speed, an endless brush so mounted with respect to the carrier that the bottles on the latter will be cleaned by the said brush, means for producing a relative transverse movement between the carrier and the brush 120

125

130

whereby the bottles will be turned during the cleaning operation, and means on said carrier for cleaning the bottoms of the bottles.

5. In a machine for cleaning bottles or like articles, a carrier for the bottles, means for driving said carrier at a relatively slow speed, a brush so mounted with respect to the carrier that the bottles on the latter will be cleaned by the said brush, mechanism for driving said brush at a relatively high speed, means for moving said brush transversely of the carrier, whereby the bottles will be turned during the cleaning operation, and 10 brushes on said carrier for cleaning the bottoms of the bottles.

6. In a machine for cleaning bottles or like articles, the combination of an endless carrier for the bottles, a brush for cleaning the exteriors of the bottles on the carrier, the brush being so positioned with respect to the carrier that the exterior of the bottles will be cleaned during their transit on said carrier, mechanism for adjusting toward and 20 from the brush the portion of the carrier which is adjacent to said brush, whereby the machine is adapted to clean bottles of different diameters, and means for holding such portion of the carrier in its adjusted 25 position.

7. In a machine for cleaning bottles or like articles, an endless carrier for the bottles, means for delivering the bottles to the carrier so that they will extend lengthwise 30 of the latter, means for driving the carrier at a relatively slow speed, a brush so positioned with respect to the carrier that the bottles on the latter will be cleaned as the bottles are carried past said brush, means for 35 producing a relative transverse movement between the carrier and brush, whereby the bottles will be turned as they are being cleaned, and means for varying the distance 40 between the carrier and the brush whereby the machine is adapted to clean bottles of 45 different sizes.

8. In a device for cleaning bottles or like articles, an endless carrier, brushes mounted upon said carrier, an endless brush so positioned with respect to the carrier that the bottles on the latter will be cleaned on their sides during their transit on the carrier, means for driving said endless brush at a 50 higher speed than the carrier, whereby the bottoms of the bottles will be forced against the brushes on the said carrier, and means for moving the endless brush transversely of the carrier so that the bottles will be turned thereon and their entire exterior cleaned by 55 said brushes.

9. In a device for cleaning bottles or like articles an endless carrier, brushes mounted upon said carrier, an endless brush so positioned with respect to the carrier that the 60 bottles on the latter will be cleaned on their

sides during their transit on the carrier, means for driving said brush at a higher speed than the carrier, whereby the bottoms of the bottles will be forced against the brushes on the said carrier, means for moving 70 the endless brush transversely of the carrier so that the bottles will be turned thereon, and their entire exterior cleaned by said brushes, and mechanism for varying the distance between the carrier and the brush so 75 as to clean bottles of different diameters.

10. In a machine for cleaning bottles and like articles, a carrier for said bottles, means for cleaning the exterior of the bottles while in transit on said carrier, plates beneath the 80 carrier opposite the said cleaning means, and means for raising and lowering said plates whereby the carrier may be moved toward or from the said cleaning means, whereby the machine is adapted to operate 85 upon bottles of different diameters.

11. In a machine for cleaning bottles and like articles, a carrier for said bottles, a brush for cleaning the exterior of the bottles while in transit on said carrier, plates beneath the carrier opposite the said brush, means for raising and lowering said plates whereby the carrier may be moved toward or from the said cleaning means, whereby the machine is adapted to operate 90 upon bottles of different diameters, and means for causing the bottles to turn while being 95 cleaned.

12. In a machine for cleaning bottles or like articles, an endless carrier for the bottles, bottle cleaning means so mounted with respect to said carrier that the bottles on the latter will be cleaned during their transit, plates beneath the carrier opposite said cleaning means, pivoted links supporting 100 said plates, a shaft, means whereby said shaft may be rocked, cranks on said shaft, and connections between said cranks and said plates whereby the latter may be raised or lowered by rocking the said links, and the carrier will thus be moved toward or from the cleaning means, so that the machine may 105 operate upon bottles of different diameters.

13. In a machine for cleaning bottles or like articles, an endless carrier for the bottles, a rotary brush so mounted with respect to said carrier that the bottles on the latter will be cleaned during their transit, plates beneath the carrier opposite said brush, pivoted links supporting said plates, a shaft, means whereby said shaft may be rocked, cranks on said shaft, connections between said cranks and said plates whereby the latter may be raised or lowered by rocking the said 110 links, and the carrier will thus be moved toward or from the brush, so that the machine may 115 operate upon bottles of different diameters, and a pawl and ratchet mechanism for holding the shaft and the carrier in position.

14. In a machine for cleaning bottles or
like articles, an endless brush, means for op-
erating said brush, means for supporting the
bottles in position to be operated upon by
said brush, and mechanism for moving said
brush while rotating so as to turn the bottles. 70
15. In a machine for cleaning bottles or
like articles, an endless brush, means for op-
erating said brush, means for supporting
the bottles in position to be operated upon
by said brush, mechanism for moving said
brush while rotating so as to turn the bot-
tles, and means for moving said bottle sup-
porting means toward and from the brush so
as to clean bottles of different diameters. 75
16. In a machine for cleaning bottles and
like articles, means for supporting the bot-
tles, a brush on said means, said bottles be-
ing adapted to lie with their bottoms against
said brush, an endless brush mounted over
said supporting means, means for driving
said brush, and mechanism for producing a
relative transverse movement between said
support and the brush whereby the bottles
are turned by the latter and the bottoms of
the bottles are cleaned by the brush on the
said supporting means. 80
17. In a machine for cleaning bottles and
like articles, means for supporting the bot-
tles, a brush on said means, said bottles being
adapted to lie with their bottoms against
said brush, an endless brush mounted over
said supporting means, means for driving
said brush, and mechanism for moving the
rotary brush transversely of the bottle sup-
porting means, whereby the bottles are
turned as they are cleaned. 85
18. In a machine for cleaning bottles and
like articles, a carrier for the bottles, an
endless brush so mounted with respect to
the carrier that the bottles are cleaned there-
by when in transit, said brush being mount-
ed upon shafts transverse to the length of
said carrier, a yoke plate connecting said
shafts at one end, said plate being provided
with a slot, a crank shaft, means for turn-
ing said shaft, and a crank on said shaft
having a pin projecting into said slot in
the plate whereby, as said crank rotates, the
brush will be shifted transversely of the
carrier and the bottles will be turned while
being cleaned. 90
19. In a machine for cleaning bottles and
like articles, a carrier for the bottles, an
endless brush so mounted with respect to the
carrier that the bottles are cleaned thereby
when in transit, said brush being mounted
upon shafts transverse to the length of said
carrier, a yoke plate connecting said shafts
at one end, said plate being provided with
a slot, a crank shaft, means for turning said
shaft, a crank on said shaft having a pin
projecting into said slot in the plate, where-
by, as said crank rotates, the brush will be
shifted transversely of the carrier and the
bottles will be turned while being cleaned. 95
- bottles will be turned while being cleaned,
and means for moving the carrier toward
and from the brush so as to clean bottles
of different diameters. 100
20. In a device for cleaning bottles or like
articles, the combination of an endless car-
rier, brushes mounted upon said carrier, an
endless brush so positioned with respect to
the carrier that bottles on the latter will
be cleaned on their sides during their transit
on the carrier, means for driving said brush
at a higher speed than the carrier whereby
the bottoms of the bottles will be forced
against the brushes on said carrier, and
means for causing relative transverse move-
ment between the carrier and the brush
whereby the bottles on said carrier will be
rotated. 105
21. In a machine, for cleaning bottles and
like articles, the combination of a carrier for
the bottles, an endless brush adjacent to said
carrier, and means for moving a portion of
said carrier toward and from said brush to
accommodate bottles of different diameters
therebetween. 110
22. In a machine for cleaning bottles and
like articles, the combination of an endless
carrier for the bottles, an endless brush
mounted in proximity to said carrier, means
for rotating said brush, and means for mov-
ing to and from said brush and for sup-
porting in position the portion of the car-
rier which is adjacent thereto. 115
23. In a machine for cleaning bottles and
like articles, the combination of a carrier
for bottles, an endless brush mounted in
proximity to said carrier, and means for
causing the bottles on the carrier to be ro-
tated in reverse directions while subjected to
the action of the brush. 120
24. In a machine for cleaning bottles or
like articles, the combination of a carrier,
an endless brush, means for rotating said
brush, and means for reciprocating said
brush transversely with respect to said
carrier. 125
25. In a machine for cleaning bottles and
like articles, the combination of a carrier, a
brushing device mounted adjacent to said
carrier, means for driving said device, means
for delivering bottles onto said carrier, and
means, including said device, for moving
the bottles laterally on said carrier. 130
26. A bottle brushing machine comprising
a carrier for bottles, a brushing device
mounted in proximity to said carrier, and
means for shifting the bottles on said car-
rier transversely of the carrier while they
are being operated upon by said brushing
device. 135
27. A bottle brushing machine comprising
a carrier for bottles, a brushing device above
said carrier, and means for shifting the bot-
tles transversely of said carrier, whereby
the bottles resting upon the carrier are 140

6
moved transversely thereof while being operated upon by said brushing device.

28. In a machine for cleaning bottles and like articles, the combination of a carrier for bottles, a brushing device mounted in proximity to said carrier, and means for reciprocating the bottles on said carrier in a lateral direction while subjected to the action of the brushing device.

10 29. In a machine for cleaning bottles and like articles, the combination of a carrier for bottles, a brushing device mounted in proximity to said carrier, means for turning said brushing device, and means, additional 15 to the turning means, for moving the bottles in a lateral direction while subjected to the brushing action of said device.

30. In a machine for cleaning bottles and like articles, the combination of a support 20 for bottles, a brushing device mounted in proximity to said support, means for producing relative movement between the support and the brushing device, and means for reciprocating the bottles on said support.

25 31. In a machine for cleaning bottles and like articles, the combination of a support for bottles, a brushing device in proximity to said support, means for turning said brushing device, means for producing relative movement between the brushing device 30 and the bottle support, and means for causing the bottles on the support to be rotated in reverse directions while subjected to the action of the brushing device.

35 32. In a machine for cleaning bottles and

like articles, the combination of a carrier for bottles, a brushing device mounted in proximity to said carrier, means for turning said device, and means for shifting the bottles transversely with respect to the carrier 40 and to the brushing device while the bottles are being operated upon by said brushing device.

33. In a machine for cleaning bottles and like articles, the combination of a carrier 45 for bottles, a brushing device mounted in proximity to said carrier, means for turning said device, and means, additional to the turning means, for moving the bottles laterally with respect to said device and said 50 carrier while being operated upon by the brushing device.

34. In a machine for cleaning bottles and like articles, the combination of a carrier, an endless brush mounted adjacent to said 55 carrier, means for reciprocating said brush transversely of the carrier, means for delivering bottles onto said carrier, and means movable with the brush, during its reciprocation, for moving said bottles laterally on 60 said carrier to bring them into position for being cleaned by the brush.

In testimony whereof, I hereunto affix my signature in the presence of two witnesses.

GEORGE R. LAWRENCE.
